UNITED STATES PATENT OFFICE.

VICTOR E. EDWARDS, OF WORCESTER, MASSACHUSETTS.

FURNACE.

SPECIFICATION forming part of Letters Patent No. 653,504, dated July 10, 1900.

Application filed March 3, 1897. Serial No. 625,804. (No model.)

To all whom it may concern:

Be it known that I, VICTOR E. EDWARDS, a citizen of the United States, residing at Worcester, in the county of Worcester and

5 State of Massachusetts, have invented a new and useful Improvement in Furnaces, of which the following is a specification, reference being had to the accompanying drawings, forming a part of the same, in which—

10 Figure 1 is a vertical sectional view of a furnace, showing the apparatus for feeding rods or billets to the furnace and withdrawing them therefrom. Figs. 2, 3, and 4 show each a horizontal section of a portion of a furnace,

15 showing the relative position of the rod or billet in its passage through the furnace, Fig. 2 showing the heated rod or billet at the point of its withdrawal from the furnace, Fig. 3 showing the rod or billet after it has passed

20 the feeding-rolls and is engaged by the push-rod, and Fig. 4 represents the rod or billet as being moved into the furnace by the action of the feed-rolls. Fig. 5 is a horizontal sectional view of a furnace, showing the relative

25 position of the feed and delivery rolls and also showing the apparatus for moving the series of rods or billets sidewise as they are successively fed into the furnace in order to bring them successively into alignment with

30 the delivery-rolls. Fig. 6 is a plan view of a portion of the furnace, showing the top view of the feed-rolls by which the rods or billets are fed to the furnace. Fig. 7 is an end view showing the feeding mechanism, and Fig. 8

35 is a partial side elevation.

Similar letters refer to similar parts in the different figures.

The object of my present invention is to provide means for feeding rods or billets to 40 a heating-furnace and delivering the same when heated from the furnace; and it consists in the construction and arrangement of parts as hereinafter described, and set forth in the annexed claims.

45 Referring to the drawings, A denotes a heating-furnace inclosing a chamber A' and provided with a floor A², which is substantially horizontal in the direction of the rods or billets contained therein, as represented

50 in Fig. 1, but preferably inclined at right angles thereto, as indicated by the broken line A³, (shown in Fig. 7,) in order to facilitate the

sidewise movement of the billets. Against one of the walls of the heating-chamber is a sole-plate B in alignment with the opening 55 B' in the wall of the furnace, and in front of the opening B' are located a pair of feed-rolls, consisting of an upper feed-roll B² and a lower feed-roll B³. These rolls are shown in the end elevation represented in Fig. 7, and their 60 position is indicated by the roll B², Figs. 3, 4, and 5. The upper feed-roll B² is journaled in fixed bearings and is rotated by means of a chain connection with the driving-shaft B⁵. The lower feed-roll B³ is journaled in a yoke 65 B⁶, mounted upon a piston inclosed in a hydraulic cylinder B⁷, having suitable connection with a source of water-supply, which is controlled by a valve B⁸, operated by an attendant by means of a hand-lever B⁹. The 70 rod or billet to be fed to the furnace is entered between the feed-rolls B² and B³. The lower roll B³ is then raised to seize the rod between the lower and upper rolls, causing the rod to be projected forward through the 75 opening B' upon the sole-plate B. When the rod has passed the feed-rolls, a push-bar C, preferably having a forked end C', is entered between the feed-rolls B² B³ with its end abutting the end of the rod C². The forward 80 movement of the push-bar, as actuated by the feed-rolls, continues the movement of the rod until it is carried wholly within the heating-chamber and upon the sole-plate B. When the rod has been pushed into the furnace, the 85 push-bar C is withdrawn by hand after reversing the valve and opening the feed-rolls.

The wall D of the furnace is provided with a series of openings D' to receive the sliding bars D², pivotally connected with arms D³, 90 projecting from the rock-shaft D⁴, which is operatively connected with a hydraulic cylinder D⁵ to impart a sliding motion to the bars D² against the rod which has been entered by the feed-rolls B² B³ in order to push the rod 95 off the sole-plate and make room for the reception of the next succeeding rod. The continued action of the feed-rolls B² and B³ and the sliding bars D² distributes a series of rods or billets over the floor of the furnace, as represented in Fig. 5.

I do not confine myself to the pushing mechanism comprising the sliding bars D², hydraulic cylinder D⁵, and intermediate con-

necting mechanism, as any known mechanism for imparting a sidewise movement to the rods or billets may be employed.

Near the opposite end of the furnace from the sole-plate B the walls are provided with openings E and E', placed opposite each other. In front of the opening E is a pair of rolls consisting of an upper roll F and a lower roll F', the upper roll F being operatively driven by the driving-shaft B⁵ and the lower roll F' being journaled in a yoke F², mounted upon a piston inclosed in a hydraulic cylinder F³ and having its movements controlled by the hand-lever F⁴, so that the roll F' can be raised or lowered similarly to the lower feed-roll B³. In front of the opening E' is a pair of positively-driven rolls G and G', journaled in a housing G².

When the advancing rod of the series is brought into alinement with the openings E and E' and has become sufficiently heated, a push-bar H, similar to the push-bar C, is entered between the rolls F and F'. The lower roll F' is then raised to cause the push-bar to be carried forward with its end abutting the end of the forward rod or billet I in the series, as shown in Figs. 1 and 2. The continued motion of the push-bar H pushes the rod I through the opening E', between the guides J, and into the bite of the rolls G and G', by which the heated rod is withdrawn from the furnace. The rolls F and F' are then opened in order to withdraw the push-bar H and allow the series of rods in the furnace to be advanced by the sliding bars D² in order to bring another heated rod or billet into alinement with the openings E E'.

The entire operation of entering the rods or billets is conducted by the attendant at the feed-rolls B² B³, and the withdrawal of the rods is controlled by an attendant at the rolls F F'. Both attendants are located upon the side of the furnace opposite that at which the heated rods or billets are delivered, and they are therefore protected from the excessive heat incident to the removal of the heated metal from the furnace by the method now in common practice.

I am aware that a push-bar moved longitudinally by the contact of a pair of revolving rolls has been heretofore employed to impart an endwise movement to a billet within a

heating-furnace, and I therefore do not claim such broadly.

What I claim as my invention, and desire to secure by Letters Patent, is—

1. The combination with a furnace having an opening at one end to receive a rod, or billet, and a pair of openings placed opposite each other at the opposite, or delivery end of the furnace, of means for mechanically pushing the rod, or billet, through said admission-opening, means for mechanically pushing the rod, or billet, sidewise from the admission to the delivery end of the furnace, a pair of withdrawing-rolls placed opposite one of the openings at the delivery end of the furnace and means operating through the opposite opening for mechanically pushing the rod or billet into engagement with said rolls by which the rod, or billet, is withdrawn from the furnace, substantially as described.

2. The combination with a furnace having an opening at one end for the admission of a rod, or billet, and a pair of openings placed opposite each other at the opposite or delivery end of the furnace, of means for pushing the rod or billet from the admission to the delivery end of the furnace, a pair of withdrawing-rolls placed opposite one of the openings at the delivery end of the furnace and adjacent thereto, guides by which the advancing end of the rod or billet is conducted from said opening into the bite of said rolls and means operating through the opposite opening for pushing the rod or billet into said rolls, substantially as described.

3. The combination with a furnace for heating rods or billets having a pair of openings in its side walls placed opposite each other and at the delivery end of the furnace, of a pair of rotating rolls placed opposite one of said openings, means operating through the opposite opening for pushing the rod or billet into the bite of said rolls, and means for guiding the advancing end of the rod or billet between the furnace and the rolls, substantially as described.

Dated this 18th day of February, 1897.

VICTOR E. EDWARDS.
